LABELING MACHINE

Owen A. McNamee, Worcester, Mass.

Application March 1, 1938, Serial No. 193,331

15 Claims. (Cl. 216—55)

This invention relates to a labeling machine and particularly to a machine for applying labels to electrical cables and the like.

In the making of rubber covered electrical cables and the like it is the practice to draw a strand of bare or cotton covered wire from a payoff reel or other source of supply and pass it through a tubing machine where a coat of warm rubber compound is applied as insulation. The coated wire then passes to a labeling machine where, at uniform intervals, generally of about five feet, unvulcanized rubber labels are positioned thereon so as to identify the wire; and it is to such a labeling machine that this invention relates. The wire with the labels attached is then suitably vulcanized and ready for use.

It is one of the objects of this invention to provide an improved labeling machine for applying labels automatically to a continuous length article, such as wire and the like.

It is another object of the invention to provide a labeling machine which will automatically apply labels to continuous length electrical cables and the like at predetermined spaced intervals.

It is a further object of the invention to provide a labeling machine which will automatically select labels one at a time from a supply of labels and apply them to continuous length electrical cables and the like at predetermined spaced intervals.

It is still another object of the invention to provide a labeling machine which is automatically controlled and actuated by the movement of the article to be labeled through the machine.

Various other objects and advantages of my invention will more fully appear during the course of the following specification and will be more particularly pointed out in the appended claims.

In the accompanying drawings I have shown, for the purpose of illustration, one embodiment which my invention may assume in practice.

In these drawings:

Figure 1 is a plan of the improved labeling machine of my invention partly in section taken on line I—I of Figure 3.

Figure 2 is a front elevation thereof.

Figure 3 is a section taken on line III—III of Figure 2.

Figure 4 is a section taken on line IV—IV of Figure 3.

Figure 5 is a side elevation of the upper end of the magazine, and

Figure 6 is a section taken on line VI—VI of Figure 2.

The labeling machine of my invention, as shown

in the drawings, comprises a frame 2 which is mounted preferably on the end of a threaded shaft support 3 which, in turn, is positioned in a suitable vertical pedestal member 4, and supported therein by means of a hand-wheel 5 mounted on the threaded portion of the support 3 which rests on the top of the member 4. The hand-wheel 5 is provided to adjust the vertical position of the frame and the labeling mechanism carried thereby.

There is mounted on the top of the frame 2, a hollow rotatable label-applying wheel 6 having a plurality of holes or perforations 7, preferably covering an area of about the size of a label, positioned on the periphery thereof and communicating with the central or hollow portion of the wheel. The wheel 6 is preferably integrally connected to a hollow shaft 8 which is supported by a movable bearing stand 9 mounted on the top of the frame 2. The bearing stand 9 has extending from the bottom thereof, through an opening in the frame, a rod 10 which is pivotally connected to one end of a lever arm 12. The lever arm 12 is fulcrumed in a bearing member 13 mounted on the lower portion of the frame and has its opposite end pivotally connected to a solenoid piston 14 of a solenoid 15 which is suitably attached to the under side of the frame. The bearing stand 9 also has lower extending guide-pins 16 attached thereto which cooperate with guide-bushings 17 positioned on the frame to guide the bearing stand 9 and wheel 6 in their vertical movement.

Directly above the shaft 8 there is mounted, on a suitable support carried by the frame, a solenoid 18 having a piston 19. The outer end of the piston 19 is pivotally connected to a hollow label-selecting member 20, having a plurality of suitable perforations 21 in its bottom wall and communicating with the central hollow portion thereof.

Extending from the top wall of the selecting member 20, and communicating with the central hollow portion thereof, is a flexible hose or tubular member 22 which is connected to the outer end of a slide-valve 23 carried by a T-valve member 24. The T-valve member 24 is mounted on the upper end of a vertically extending pipe 25 which is supported by a coupling 26 mounted on the outer end of the bearing stand 9 in line with the shaft 8. The coupling 26 communicates with both the hollow portion of the shaft 8 and the vertical extending pipe 25 and is connected to a suction fan or blower 27 preferably by means of a flexible hose connection 28.

There is positioned on the frame adjacent the

outer face of the labeling wheel 6, just below the normal position of the selecting member 29, a magazine 29 for storing a supply of suitable unvulcanized rubber labels. The selecting member 5 is mounted for movement in a guide member carried by the upper side portions of the magazine as shown in Figures 4 and 5. On each side of the magazine there is positioned a vertical screw 30 with a lifting-plate or table 31 assembled therebetween in the magazine which is adapted to support a stack of labels. Each end of the label supporting table 31 has a half nut 32 pivotally attached thereto which is adapted to engage respectively with each of the screws 30. 10 There is also carried adjacent each end of the plate a leaf spring 33 which is adapted to normally keep the half nuts 32 in engagement with the threads of the screws 30. The upper end of each of the screws 30 carry a lever arm 34, loosely pivoted thereon, and ratchet gears 34a. Each of the lever arm 34 carries a pawl 35 and a leaf-spring 36 which is adapted to normally keep the pawls 35 in engagement with the respective ratchet-gears 34a. The outer ends of the lever 15 arms 34 have slotted holes 37 by which they are connected together by means of a cross-bar or arm 38.

The piston 19 of the solenoid 18 carries a collar 39 and a coil spring 40 which is adapted to fit between the inside of the collar and the end of the solenoid. The collar 39 carries an upwardly extending arm 41 having a pin 42 on the end thereof which is adapted to fit in a slotted hole 43 of a cam-bar 44. One end of the cam-bar 44 is loosely pivoted, at 45, to a suitable support directly above the solenoid 18 carried by the frame, and the opposite end thereof has a slotted hole 46 therein through which a pin 47, carried by the cross-bar 38 intermediate its ends, is adapted to extend.

40 Preferably, on the wire entering side of the machine there is positioned a mechanism for controlling the machine. This mechanism comprises a shaft 48 positioned in a pair of spaced-apart bearing supports 49 suitably mounted on the frame of the machine. There is pivotally mounted on the shaft 48 a supporting frame 50. The frame 50 carries on its outer end, parallel to the shaft 48, a stub shaft 51 rotatably mounted in suitable bearing supports 52. One end of shaft 51 carries a measuring wheel 53, the periphery of which is adapted to rest on the wire as it passes into the machine. The opposite end of the shaft 51 carries a bevel-gear 54 which is adapted to mesh with a bevel-gear 55 on the end of a stub-shaft 56 which is arranged perpendicularly to shafts 51 and 48 and rotatably mounted in suitable bearing supports 57 positioned on the frame 50. On the opposite end of the stub-shaft 56 there is mounted a bevel-gear 58 which meshes 45 with a bevel-gear 59 positioned on the shaft 48.

50 On the outer end of the rotatable shaft 48 there is arranged a gear 60 which is adapted to mesh with a gear 61 mounted on the outer end of a rotatable stub-shaft 62 which is arranged in suitable bearings 63 mounted on an extending portion of the frame 2 of the machine. There is also arranged on the stub shaft 62 a timing-wheel 64 having a pair of contacting segments 65 on the periphery thereof which are adapted to contact 55 respective brushes or contacting members 66 which are suitably arranged on this extending portion of the frame 2. One of the contacting members or brushes 66 is connected electrically to the solenoid 15 and the other to the solenoid 18. 60 The segments 65 on the wheel 64 are adapted to

contact the brushes or contacting members 66 upon rotation of the timing-wheel, thereby closing the circuit through either one or the other of the solenoids to energize them.

The frame 2 carries guide sheaves or rollers 67 thereon for supporting the wire as it passes into and through the machine. There is arranged directly below the labeling-wheel 6, on the side of the frame, a supporting sheave or roller 68 rotatably mounted on an adjustable bracket 69. The 10 sheave 68 is made adjustable in order that various sizes of wires can be labeled in the machine. There are positioned, directly opposite the two outer sheaves or rollers 67 on the delivery side of the machine, ironing rollers or sheaves 70. One 15 of them is preferably mounted on the end of a stud-shaft 71 which is arranged in a bracket 72. One end of the bracket 72 is pivotally connected to the machine at 73 and its outer end carries a suitable weight 74. The purpose of the ironing 20 sheaves 70, of course, is to firmly press the unvulcanized rubber labels into contact with the surface of the rubber covered wire, the labels and wire passing thereunder.

The labeling machine of my invention operates 25 in the following manner. It will be assumed that the magazine is filled with a supply of suitable unvulcanized rubber labels. The rubber covered wire is fed into the machine and pulled there-through, preferably by means of a suitable power 30 driven coiling draw-off drum (not shown). The frame 50, carrying the controlling mechanism, is swung to substantially a horizontal position so that the measuring wheel 53 rests on the wire to be labeled. The suction fan or blower 27 is set 35 in operation and the machine is ready for labeling the wire. As the wire passes through the machine it turns the wheel 53 which rotates the timing wheel 64 through the action of bevel-gears 54, 55, 58, and 59, and the spur gears 60 and 61. 40 When one of the segments 65, carried by the timing wheel 64, contacts one of the respective brushes 66, it closes the circuit and energizes the solenoid 15 and raises the bearing stand 9, the hollow shaft 8, and labeling wheel 6, through the 45 action of the solenoid piston 14, lever arm 11 and rod 10. In the meantime the selecting member 29 has picked a label from the top of the supply of labels in the magazine, by means of the suction produced by the fan or blower 27 in the air lines 28, 25 and 22, and holds it against the perforations 21 on the bottom face thereof. As the timing wheel 64 rotates farther, the second segment 65 on the timing wheel contacts the second respective brush 66 and closes the circuit which 50 energizes solenoid 18, forcing the piston 19 to the right and carrying the selecting member 29 to a position directly opposite the perforations 7 in the periphery of the labeling wheel 6. As the selecting member moves to the right it closes the slide-valve 23 in the T-member 24 and the suction force 55 is shut off, thereby allowing the label to be transferred to the periphery of the labeling wheel by means of suction induced in the hollow shaft 8 and the hollow central portion of the labeling wheel 6 by the fan 27. By this time the solenoid 15 is de-energized, allowing the labeling wheel to drop down on the wire. As the wire passes through the machine it turns the labeling wheel, bringing the label around and transferring it to the surface of the wire, cementing it thereon due to their adhesive properties. The wire, together with the label thereon, then passes between the ironing sheaves, thereby firmly pressing the label into engagement with the rubber insulation of the wire. 60

When the selecting member 20 moves from its normal position to the position directly above or opposite the perforations 7 in the periphery of the labeling wheel 6, the pin 42 on the end of the arm 41, carried by the collar 39 of the solenoid piston 19, rotates the lever arm 44 about its pivot 45, thereby moving the cross-bar 38 which, in turn, moves the lever arms 37 which engage the pawls 35 carried thereby, with the ratchet wheels 34^a on the end of the shafts 30 turning the same, raising the lifting-plate 31 a height substantially equivalent to the thickness of one label. The vertical movement of the lifting-plate 31 can be adjusted by varying the length of the lever arms 37. After the label has been transferred to the labeling wheel, the solenoid 18 becomes de-energized and the selecting member 20 is returned, by means of the coil spring 40, to position above the magazine in order to pick up the next label. In the meantime, the solenoid 15 is again energized as described, thus raising the suction labeling-wheel 6 to its upper position. The momentum gained by the labeling wheel, while in contact with the moving rubber insulated wire, will be sufficient to rotate it so as to position the perforations in the periphery thereof at the top of the wheel. In order to position the labeling wheel correctly so that the perforations in the periphery thereof will be superimposed under those of the selecting member when the latter is brought to position thereover, there is provided a stop finger 81 on the inner surface of the labeling wheel 6 which cooperates with a stop catch 82 suitably arranged on the frame of the machine. It will be seen that, when the labeling wheel is lowered, the stop finger 81 will become disengaged from the catch 82, allowing the wheel to turn to apply the label. It will also be seen that the labels can be placed on the wire at any spacing desired, by selecting the proper measuring wheel 53.

When the supply of labels in the magazine 29 is exhausted, the half nuts 32 are swung away from the screws 30, thus allowing the lifting-plate 31 to drop to its lowermost position in the magazine, thereby permitting a fresh supply of labels to be deposited therein. It will be understood that this machine is automatic and continuous in its operation and that the above described cycle is repeated for the application of each label to the wire.

While I have shown and described an embodiment of my invention, it will be understood that this embodiment is merely for the purpose of illustration and description and that various other forms may be devised within the scope of my invention, as defined in the appended claims.

I claim:

1. A label applying machine comprising means for holding a supply of labels, a reciprocable actuated suction means for selecting labels one at a time from said supply means, means for applying said labels to a continuous length article, and suction means for transferring said labels directly from said selecting means to said applying means.

2. A label applying machine comprising means for holding a supply of labels, a reciprocable actuated means for selecting labels one at a time from said supply means, means for applying said labels to a continuous length article, means for moving said selecting means opposite said applying means, and means for transferring said labels directly from said selecting means to said applying means.

3. A label applying machine comprising means for holding a supply of labels, a reciprocable actuated suction means for selecting labels one at a time from said supply means a rotatable wheel for applying labels to a continuous length article, means for moving said selecting means opposite the periphery of said wheel, and suction means for transferring said labels directly from said selecting means to the periphery of said rotatable applying wheel.

4. A label applying machine comprising means for holding a supply of labels, a reciprocable actuated means for selecting labels one at a time from said supply means, a rotatable wheel for applying said labels to a continuous length article, and suction means for transferring said labels directly from said selecting means to the periphery of said wheel, said wheel rotated by movement of the article to be labeled through the machine whereby said labels are placed upon the article at predetermined spaced intervals.

5. A label applying machine comprising means for holding a supply of labels, means for selecting labels one at a time from said supply means, means for applying said labels to a continuous length article, means for transferring said labels from said selecting means to said applying means, and electrical means for actuating said transferring means, said electrical means controlled and said applying means actuated by movement of the article to be labeled through the machine whereby said labels are placed upon the article to be labeled at predetermined spaced intervals.

6. A label applying machine comprising means for holding a supply of labels, suction means for selecting labels one at a time from said supply means, a rotatable wheel for applying said labels to a continuous length article, suction means for transferring said labels from said selecting means to the periphery of said applying wheel, an electrical means for controlling the action of said selecting suction means, said electrical means controlled and said applying wheel rotated by movement of the article to be labeled through the machine whereby said labels are placed upon the article at predetermined spaced intervals.

7. A label applying machine comprising a magazine for holding a supply of labels, suction means for selecting labels one at a time from said magazine, means for moving said labels in said magazine toward said selecting means, a rotatable wheel for applying said labels to a continuous length article, electrical means for moving said selecting means opposite the periphery of said wheel, said electrical means controlled by movement of the article to be labeled through the machine, and suction means for transferring said labels from said selecting means to the periphery of said rotatable applying wheel, said wheel rotated by movement of the article to be labeled through the machine whereby said labels are placed upon the article at predetermined spaced intervals.

8. A label applying machine comprising means for holding a supply of labels, suction means for selecting labels one at a time from said supply means, a rotatable wheel for applying said labels to a continuous length article, means for transferring said labels from said selecting means to the periphery of said applying wheel, and electrical means for controlling said first mentioned suction means and for actuating said transferring means, said electrical means controlled and said applying wheel rotated by movement of the article to be labeled through the machine where-

by labels are placed upon the article at predetermined spaced intervals.

9. A label applying machine comprising means for supplying labels to the machine, reciprocating

- 5 means for selecting labels one at a time from said supplying means, means for applying said labels to a continuous length article and means for transferring said labels from said reciprocating selecting means to said applying means, said 10 transferring means controlled and said applying means actuated by movement through the machine of the article to be labeled whereby said labels are placed upon the continuous article to be labeled at predetermined spaced intervals.

15 10. A label applying machine comprising means for supplying labels to the machine, a reciprocable suction means for selecting labels one at a time from said supplying means, a rotatable wheel for applying the labels to a continuous length article, means for positioning said

- 20 reciprocating selecting means opposite the periphery of said rotatable wheel, and suction means associated with said wheel for transferring the labels directly from said selecting means

25 to the periphery of said applying wheel, said selecting means controlled and said applying wheel rotated by movement through the machine of the article to be labeled whereby the labels are placed upon the article at predetermined spaced intervals.

11. A label applying machine comprising means for supplying labels to the machine, a reciprocating movable member having suction means associated therewith for selecting labels

- 35 one at a time from said supplying means, a rotatable wheel for applying said labels to an article to be labeled, and means for reciprocably moving said selecting member to a position opposite the periphery of said rotatable wheel so as 40 to transfer said labels directly to the periphery thereof, said wheel rotated by movement through the machine of the article whereby said labels are placed thereon.

12. A label applying machine comprising means for holding a supply of labels, a reciprocating movable member having suction means

- 45 associated therewith for selecting labels one at a time from said supplying means, a rotatable wheel for applying said labels to a continuous length article, said rotatable wheel having perforations in the periphery thereof covering an area substantially equal to the size of a label and suction means associated therewith for hold-

ing a label thereon, and means for reciprocably moving and positioning said movable selecting member in position opposite the perforations in the periphery of said rotatable wheel whereby said labels are transferred directly from said 5 selecting member to the periphery of said rotatable wheel, said selecting member controlled and said applying wheel rotated by movement through the machine of the article to be labeled whereby said labels are securely placed upon the 10 article at predetermined spaced intervals.

13. A label applying machine of the class described comprising a rotatable wheel for applying labels to a continuous length article, means arranged adjacent said wheel for holding a supply 15 of labels, a selecting member arranged for reciprocable movement above said label supply means and said wheel and having suction means associated therewith for selecting labels one at a time from said supply means, means for moving 20 said selecting member from position above said supply means to position opposite the periphery of said wheel, said wheel having suction means associated therewith for transferring the labels successively from said selecting means to the 25 periphery thereof and means for rotating said wheel whereby said labels are placed upon the article at predetermined spaced intervals as it passes in contact therewith.

14. A label applying machine of the class described as defined in claim 13, wherein the means for moving said movable selecting member to position above said wheel comprises a solenoid.

15. A label applying machine of the class described comprising a rotatable wheel for applying labels to a continuous length article, a magazine arranged adjacent said wheel for holding a supply of labels, a selecting member arranged for reciprocable movement above said magazine and said wheel and having suction means associated therewith for selecting labels one at a time from said supply means, a solenoid for moving 35 said selecting member from position above said supply means to position opposite the periphery of said wheel, said wheel having means associated therewith for transferring said labels successively from said selecting means to the periphery thereof and means associated with the 40 plunger of said solenoid for actuating means for moving the supply of labels in said magazine 45 upwardly therein upon movement of said plunger.

OWEN A. McNAMEE.
